E. A. KUEN.
ELECTRIC CONNECTOR.
APPLICATION FILED MAY 24, 1920.

1,422,992.

Patented July 18, 1922.

UNITED STATES PATENT OFFICE.

EUGENE A. KUEN, OF CINCINNATI, OHIO, ASSIGNOR TO THE THOS. J. CORCORAN LAMP COMPANY, OF CINCINNATI, OHIO, A CORPORATION OF OHIO.

ELECTRIC CONNECTOR.

1,422,992.

Specification of Letters Patent. Patented July 18, 1922.

Application filed May 24, 1920. Serial No. 383,908.

To all whom it may concern:

Be it known that I, EUGENE A. KUEN, a citizen of the United States, residing at Cincinnati, in the county of Hamilton and State of Ohio, have invented certain new and useful Improvements in Electric Connectors, of which the following is a specification.

My invention relates to electric connectors, especially to such connectors having two terminals or posts.

It is the object of my invention to provide novel means whereby separation of the terminals is assured, so as to prevent the short-circuiting of the terminals; further, to provide novel means for securing in place a separating strip between the terminals; and, further, to provide novel means for securing the electric conductors to the terminals.

The invention will be further readily understood from the following description and claims, and from the drawing in which latter:

Fig. 1 represents a side elevation of a connector, partly broken away, embodying my improved device.

Fig. 2 represents an edge elevation of the same.

Fig. 3 represents a rear end elevation of the same.

Fig. 4 is a front end elevation of the same.

Fig. 5 is an axial section of the same, taken on the line 5—5 of Fig. 4.

Fig. 6 is an axial section of the same, taken on the line 6—6 of Fig. 4.

Fig. 7 is a cross-section of the same, taken on the line 7—7 of Fig. 1. Fig. 8 is a detail in section on the line 8—8 of Fig. 7; and,

Fig. 9 is an axial section of a modification of my improved device showing my invention applied to a connector arranged to receive plugs at the respective ends thereof.

My improved device is especially applicable in connection with connectors used for electric lamps employing electric lamp-bulbs having two end-terminals, and used as head-lights, spot-lights and the like for automobiles and other vehicles. Such a bulb is exemplified at 11, having the end terminals 12, 13, which connect with the filament of the lamp.

The connector comprises a tube 15, which is adapted to be received and positioned in usual manner in a usual cylindrical flange at the rear end of the reflector of the lamp.

The plug 16 of the electric light bulb is received in the end of the tube, and has suitable mechanical connection therewith, indicated by the pin and bayonet slot connection 17.

An insulating block or washer 21, indicated as a comparatively thin washer, for instance of insulating fiber, is fixed in the tube, for instance my means of indenting the body of the tube with inwardly extending prongs 22, against which one end of the washer is received, and prongs 23 bent against the other end of the washer for positioning the washer endwise in the tube.

Terminal posts 25, 26, are received in the washer. Each of the posts comprises a sleeve 27, which is provided with an annular shoulder 28, and a peripheral seat 29, which latter is preferably of greater diameter than the outer end 30 of the sleeve. A spring 31 is located in the sleeve between the bottom end of the bore 32 in the sleeve and a plunger 33. The plunger is provided with an inner annular shoulder 34 arranged to contact an annular flange 35 at the outer end of the bore, forming a stop for the outward movement of the plunger, this stop being formed by spinning or upsetting the outer edge of the wall of the bore after the plunger has been placed in the bore.

The insulating washer is provided with holes 39 into which the ends of the terminal posts are received, the posts being forced into these holes so that the peripheral seats 29 make firm contact with the walls of the holes, the shoulders 28 bearing against one end of the washer.

The outer end of each of the sleeves is provided with a transverse hole 41. 42 is an electric conductor provided with an insulating covering 43. The insulating covering, which is preferably a woven tubular fabric, is removed from the extreme end of the electric conductor, so as to electrically expose this end. The electric conductor is preferably a number of fine wires twisted or woven together.

A ferrule 45, of electro-conductive metal, 100 comprises a tubular portion 46, and a cup-portion 47, having an inner annular shoulder 48 between them. The outer end of the cup-portion is preferably curled outwardly, as shown at 49, to form an outwardly flaring annular flange. The elec-

tric conductor is arranged to be passed through the tubular portion, with the outer end of the insulating covering impinging against the shoulder, for positioning the 5 electric conducting wire in the tubular portion and the insulating covering in the cup-portion.

The tubular portion is inserted in the transverse hole in the terminal post, the 10 outer annular shoulder 51 at the end of the tubular portion impinging against the side of the terminal post. The outer end of the electric conductor is bent across the outer end of the tubular portion and the opposite face 15 of the terminal post, and across the end of the terminal post, where the ends of the wire or wires are soldered to the end of the terminal post by a suitable solder, shown at 52. This positions the end of the insulating 20 material within the ferrule against the shoulder 48, and fixes the endwise relation between the electric conductor, the insulating material, the ferrule, and the post. It further insures excellent electric connection 25 between the electric conductor and the terminal post. The ferrule aids in directing flexure of and in supporting the electric conductor and insulating material, to prevent abrupt bends therein, distinctly aided by the 30 outwardly curved annular flange at the outer end of the cup-portion.

The insulating body or washer, in which the sleeves are located, is provided with a radial slot 55. An insulating plate 56, 35 formed for instance of insulating fibre, is positioned in the slot, and has a projection extending radially at the end of the insulating body or washer, and between the terminals or posts. Radially extending portions 40 57, 58, of the insulating plate are shown at the respective ends of the insulating body or washer, for locating a separating insulation between the portions of the electric terminals or posts at both ends of the insulating 45 body or washer. The invention is peculiarly useful when employing a thin fibre washer as the support for the terminal posts.

This separating insulating strip is preferably of substantial U-form, the limbs of the 50 U being received at both ends of the insulating block or washer between the portions of the binding posts or terminals at both ends of the washer. The base or shank 59 of the U is located in the slot in the washer.

55 The insulating separating strip is positioned in the washer prior to the insertion of the washer into the tube 15. The construction is such that the insulating strip is radially insertible, and connected with the 60 insulating block or washer by radial movement of the insulating strip, for locating the shank 59 of the insulating strip in the slot 55 in the washer. The washer and insulating strip are inserted and the washer fastened in the tube, thereby also fastening the

insulating strip in place, against radial movements and against lateral and lengthwise movements.

The pressure of the plug of the electric lamp when inserted in the connector is toward that end of the insulating block or washer at which the annular shoulders 28 on the sleeves are located.

In case there should be any looseness of fit between the electric terminals or posts 75 and the insulating block or washer and a tendency on the part of the electric terminals or posts to wobble or be forced out of parallelism with each other, the insulating strip between the same preserves the electric separation 80 between them and prevents an arcing or short-circuiting of electricity between the electric terminals or posts, and between the posts and the tube, and the location of said radial insulating strip between the ferrules 85 45 also prevents an approach between the ferrules which might cause short-circuiting between said ferrules.

Referring to Fig. 9, I have illustrated my invention as applied to double-ended posts, 90 the corresponding parts being indicated by corresponding but primed reference numerals. In this instance, the washer 21' is held in place between the prongs 22' and prongs 61 struck inwardly from the body of the 95 tube. The electric posts are provided with plungers at each end thereof. The ends of the sleeves opposite to the ends in which the plungers 33' are received, have the bores 32' continued therein for receiving plungers 100 62, provided with annular shoulders 63 arranged to be stopped by annular flanges 64 at the opposite ends of the sleeves, forming stops to limit outward movement of the plungers 62. A spring 31' is in this instance located between the two plungers, for normally urging both plungers outwardly. A suitable electric conducting plug 65 is releasably secured to the opposite end of the tube 15' by the bayonet slot and pin connection 66. The plug is provided with terminals 67, 68, with which electric conductors 69, 70, are suitably connected.

Having thus fully described my invention, what I claim as new and desire to secure by Letters Patent is:

1. In an electric connector, the combination of an insulating body, a pair of electric terminals positioned thereby, and a substantially U-shaped insulating strip, said insulating body provided with a slot, the base of said strip located in said slot, and the limbs of said strip extending beyond the respective ends of said insulating body so as to be located between said electric terminals. 120

2. In an electric connector, the combination of a tube, an insulating body therein, a pair of terminal posts in said insulating body, said insulating body provided with a slot, and an insulating strip having a 125 130

shank in said slot and extensions at the respective ends of said insulating body, said shank held in said slot by said tube and said insulating strip held endwise on said body by said extensions.

3. In an electric connector, the combination of a tube, an insulating body therein, a pair of terminal posts in said insulating body and extending from said insulating body from the respective ends thereof, said insulating body provided with a slot, and an insulating strip provided with a shank and limbs at the respective ends of said shank, said shank located in said slot and

held therein radially by said tube and said limbs located at the respective ends of said insulating body and extending past the longitudinal projection of said slot whereby to locate said limbs between said extensions of said terminal posts at the respective ends of said insulating body.

In testimony whereof, I have hereunto signed my name in the presence of two subscribing witnesses.

EUGENE A. KUEN.
